UNITED STATES PATENT OFFICE.

JOSEPH C. COULOMBE, OF LOWELL, MASSACHUSETTS.

SIGNAL-HORN.

1,301,106.

Specification of Letters Patent. Patented Apr. 22, 1919.

Application filed April 19, 1915. Serial No. 22,241.

To all whom it may concern:

Be it known that I, JOSEPH C. COULOMBE, citizen of the United States, residing at Lowell, county of Middlesex, Commonwealth of Massachusetts, have invented certain new and useful Improvements in Signal-Horns, of which the following is a specification.

This invention relates to signaling devices and particularly to horns of the diaphragm type.

In my present invention the sound producing elements are slidably mounted on a rotor and are forcibly projected beyond the circumference of the rotor by the centrifugal force developed when the rotor is revolved and progressively contact and impart vibrations to a diaphragm. The sound producing elements of my invention are capable of use in either the electrical or the so called "mechanical horns," but for the purposes of this application, I shall show and particularly discuss my invention in its embodiment in a mechanically operable structure.

The present invention contemplates certain improvements in the sound producing elements themselves and in the drive for the rotor so as to secure a positive and speedy response of the impact elements upon an actuation of the rotor revolving device. I also provide for using more than one diaphragm if desired and for using diaphragms of varying diameter and thickness. These and other features which will appear more fully hereinafter are secured in the present invention.

The construction and operation of my signal will be more fully disclosed in the specification which follows. In the drawings forming a part of that specification I have shown as illustrative embodiments, several forms of signal which have proven efficient and satisfactory in use. Throughout specification and drawings like reference numerals are correspondingly applied, and in these drawings:

Figure 1 is a side elevation partially in section of a signal in accordance with my invention.

Fig. 2 is a partial section of one of the clutch elements of my signal, on the line 2-2 of Fig. 3.

Fig. 3 is a plan section thereof.

Fig. 4 is a detail view of a part more fully described hereinafter.

Fig. 5 is a plan view of the rotor with parts broken away.

Fig. 6 is a plan view of a modification showing two diaphragms. 60

Fig. 7 is an elevation partly in section on the line 7-7 of Fig. 6.

Fig. 8 is a section showing diaphragms of different thickness, and,

Fig. 9 is a partial section similar to Fig. 65 8 but showing a diaphragm of larger diameter.

I have indicated at 1 a standard adapted to be attached to an automobile or other vehicle so as to bring the actuating member of 70 the signal in conveniently operable relation to the driver's seat. The standard is formed in two similar sections welded or otherwise secured to each other. Each section is pressed out laterally as indicated at 1¹ to 75 define when the sections are united a hollow casing in which a bushing 2 is rigidly mounted. Each section of the standard terminates at its upper end in an oppositely extended flange 2¹ upon which is mounted a 80 hollow head or casing 3 in which the sound producing elements and rotor of the signal are located.

The casing 3 is formed as a suitably shaped shell closed at its rear end and open 85 at its front end. At its front end the casing is formed with an upwardly extending flange 3¹ terminating in a laterally disposed circumferential rim 4. The rim 4 incloses the inner flanged end 5 of an outwardly 90 flaring trumpet or horn 6. The flange 5 seats a vibratory disk or diaphragm 7 flatly against the flange 3¹ in complete sealing relation to the front open end of the casing. The diaphragm is clamped between the 95 flanges 3¹ and 5 by suitable fastenings 8 and is spaced from said flanges by washers 9.

Set centrally of the diaphragm is a contact member in the form of a stud 10 having its inner end beveled in opposite directions 100 as shown and disposed in the operative path of a peripheral series of centrifugally acting impact elements or hammers 12 slidably mounted on a suitable rotor element.

The rotor element is in the form of three 105 disks 13, 13¹ and 14 pinned together to rotate in unison. The intermediate disk 13¹ and the top disk 14 are spaced by a washer 15. The bottom disk 13 has a pair of suitably bent yokes 16 secured to its under face 110 and engaging a groove 17 near the upper end of the bushing 2 whereby to support and

guide the rotor. The intermediate disk 13¹ is peripherally slotted at regular intervals to provide a circumferential series of spaced lugs 18 projecting radially in the plane of the disk and the metal between the lugs 18 is bent up to provide lugs 19 disposed at substantially right angles to the disk.

The hammers 12 are slidably mounted on the intermediate disk, 13¹ and are disposed 10 radially about the spacing washer 15 mounted on said disk. The washer 15 serves as a stop to limit the inward radial movement of the hammers and the inner ends of the hammers are curved to conform to the curved 15 edge of said washer. Each hammer extends radially outward as shown and terminates at each lateral edge in an abrupt shoulder 20. Beyond the shoulders 20 the hammers are reduced and extend as rounded heads 20 21 adapted to progressively contact the beveled inner end of the stud 10 with a radially yielding contact when the rotor is revolved. The hammers are thrown radially outward by the centrifugal force developed when 25 the rotor is revolved. Each hammer slides between a pair of the vertical lugs 19 of the disk 13¹ out along and beyond the edge of the horizontal lug 18 between said vertical lugs until stopped by its shoulders 20 contacting the vertical lugs.

The rotor is revolved by positively connecting it with a suitable source of power. For effecting this the rotor preferably has a clutch member adapted to be positively engaged by the complementary clutch member 35 of a rotatable element whereby to revolve the rotor. The rotor clutch member may conveniently be a ratchet 22 fixed to the top disk 14 of the rotor and adapted to be engaged 40 by an oppositely faced ratchet 23 spun in or otherwise secured to a rotatable and downwardly movable ratchet nut 24.

In the present illustrative embodiment the means for rotating the ratchet nut 24 45 is a hand operated plunger 25 vertically reciprocable in a bushing 26 set in the top wall of the shell 3 and guided in the bushing 2 in the opposite wall of the shell. The plunger 25 is guided between its ends in a 50 bearing 14¹ secured to the rotor and has an operating knob 27 at its upper end disposed in convenient reach of the driver. The reciprocatory motion of the plunger is transformed into rotary motion whereby to revolve 55 the ratchet nut and thus the rotor by any suitable motion converting means. In this embodiment, a spiral groove 28 is cut in the plunger from end to end thereof and the ratchet nut has two intersecting threads 60 29 adapted to engage in said groove. The pitch of the threads 29 corresponds to the pitch of the groove 28.

The downward movement of the plunger is resisted by a headed stop pin 30 having a

coil spring 31 thereabout and located in the 65 bushing 2. The spring returns the plunger to raised position after each actuation. The return movement of the plunger is stopped by the upper face of the ratchet nut contacting the bushing 26. The plunger is prevented from moving out of the ratchet nut on its return by a screw 25¹ set in said plunger and contacting the threads 29 of the ratchet nut 24.

In use, a downward push on the knob 25 75 carries the plunger downwardly against the spring 31 and moves the clutch member 23 carried by the ratchet nut 24 into engagement with the fixed clutch member 22 on the rotor element.

The downward reciprocation of the plunger through its groove engaging the threads of the ratchet nut causes said nut to revolve and the nut through the engagement of its ratchet piece 23 with the ratchet 22 on the 85 disk 14 revolves the motor. The centrifugal force developed by the rapidly revolving rotor causes the impact elements 12 thereon to be projected radially outward beyond the periphery of the rotor and progressively 90 strike the contact stud 10 of the diaphragm. The hammers are positively guided by the lugs 18 and 19 in this movement.

In the modified form of my invention shown in Figs. 5, 6, 7 and 8, two diaphragms 95 32 are so arranged relative to the rotor as to be vibrated by the impact elements when the rotor is revolved. The shell 3 in this embodiment is formed at both ends with an annular flange 33 between which and the similar flanges 34 of suitable closures 35 the two diaphragms 32 are secured by the same fastenings 36 which connect the flanges 33 and 34. In this form of my invention the horn 6 is carried into one of the lateral walls of the shell. If desired one diaphragm may be of greater thickness than the other as shown in Fig. 8 or of greater diameter, as shown in Fig. 9, whereby to vary the sound.

Various other modifications in the form and construction of my device may obviously be made within the limits of the appended claims.

What I therefore claim and desire to secure by Letters Patent is:

1. In a warning signal having a diaphragm and having a plurality of slidable hammers for flexing said diaphragm, a rotatable member upon which said hammers slide having a peripheral series of spaced up-turned lugs between which the hammers slide, each lug of a length to limit the outward sliding movement of a pair of adjacent hammers.

2. In a warning signal having a diaphragm and having a plurality of slidable hammers for flexing said diaphragm, a ro-

5 tatable disk upon which said hammers slide and having an annular series of spaced upturned lugs between which the hammers slide, each lug of a length to limit the outward sliding movement of a pair of adjacent hammers.

3. In a warning signal, a casing having openings of different diameter at its ends, suitable closures for said openings, a pair 10 of diaphragms of different diameters, each seated by a closure over its respective opening, said casing constituting a sound chamber common to both diaphragms, and having a sound outlet entering said casing laterally thereof and disposed between said 15 diaphragms, a rotor arranged in said casing, and an impact element carried by said rotor and adapted to vibrate said diaphragms.

20 4. In a warning signal, a casing open at each end and having an annular flange surrounding each opening, closures for said openings each having an annular flange opposing the flange of the casing and adapted 25 to be secured thereto, a diaphragm seated over each opening by said closures, said casing constituting a sound chamber common to both diaphragms, and having a sound outlet, a rotor arranged in said casing, and 30 an impact element carried by said rotor and adapted to vibrate said diaphragms.

5. In a warning signal, a casing having a diaphragm at each end and having a lateral opening intermediate its ends, an amplifier 35 mounted in said opening, said casing constituting a sound chamber common to both diaphragms and to said amplifier, and means for flexing both diaphragms.

6. In a warning signal of the class 40 described, a casing having a diaphragm, a rotor in said casing, striking mechanism mounted on said rotor and adapted to operate said diaphragm, an attaching standard secured to said casing and comprising stampings having portions of opposed cylindricity defining an axial socket, and rotor 45 revolving means operating in said socket.

7. In a warning signal of the class 50 described, a casing having a diaphragm, a rotor in said casing, striking mechanism mounted on said rotor and adapted to operate said diaphragm, an attaching standard secured to said casing and comprising duplicate stampings having pressed-out portions 55 of opposed cylindricity defining an axial socket, a bushing fixed in said socket, and a

rotor-revolving means operating in said bushing.

8. A rotor element comprising a carrier, a pair of opposed yokes secured thereto, a bushing having a groove receiving the free 60 ends of said yokes, a rotor revolving member operating in said bushing, and impact elements guided upon said carrier.

9. A rotor element comprising a carrier, 65 a pair of opposed U-shaped yokes secured to the under face of said carrier, a bushing extending axially of said rotor and having a groove receiving the free ends of said yokes, a rotor revolving member operating 70 in said bushing, and impact elements mounted upon said carrier.

10. In a warning signal having a diaphragm element, consisting of a pair of superposed disks fastened to rotate in unison, means spacing said disks, one of said disks having peripheral slots providing a circumferential series of spaced lugs disposed in the plane of the said disk and the material of said disk bent upwardly on each 80 side of said lugs to provide stop portions, and impact elements for flexing said diaphragm mounted in radial assembly between said spaced disks and maintained in said assembly by said spacing means and adapted 85 for sliding travel upon said lugs and limited in said travel in one direction only by said stop portions.

11. In a warning signal having a diaphragm element, consisting of a pair of 90 superposed carriers fastened to rotate in unison, means spacing said carriers, and a series of slidable impact elements for flexing said diaphragm arranged in radial assembly about said spacing means as a center 95 and limited in their inward travel only thereby.

12. In a warning signal having a diaphragm element consisting of a pair of superposed disks fastened to rotate in unison, a washer spacing said disks, and a series of slidable impact elements for flexing said diaphragm arranged and maintained in radial assembly about the washer 100 as a center, and limited in their inward 105 travel only thereby.

In testimony whereof I affix my signature in presence of two witnesses.

JOSEPH C. COULOMBE.
